UNITED STATES PATENT OFFICE.

GEORGE KLEIN, JR., OF NEW YORK, N. Y.

ALARM MECHANISM FOR CARS.

SPECIFICATION forming part of Letters Patent No. 614,871, dated November 29, 1898.

Application filed April 6, 1898. Serial No. 676,627. (No model.)

To all whom it may concern:

Be it known that I, GEORGE KLEIN, Jr., a citizen of the United States, residing at New York, in the county of New York and State 5 of New York, have invented certain new and useful Improvements in Mechanisms for Operating Alarm-Bells on Cars, of which the following is a full and complete specification, such as will enable those skilled in the art to 10 which it appertains to make and use the same.

My invention relates to a device for sounding an alarm-bell suitably located upon a car; and the object thereof is to provide a simple, effective, and reliable means especially adapted 15 for the use of cable or other street cars, whereby an alarm-bell may be sounded by the motorman or driver.

The invention consists of a mechanism for sounding an alarm-bell constructed substantially as described, and defined in the claims. 20

The invention is fully disclosed in the following specification, of which the accompanying drawings form a part, in which the separate parts of my improvement are designated 25 by the same letters of reference in each of the views, and in which—

Figure 1 is a side view of the forward portion of a motor-car provided with my improved mechanism for sounding the alarm-bell, and Fig. 2 is a bottom view thereof.

In the drawings, A represents a car of any ordinary or preferred construction.

a is a foot-lever pivoted in a slot in the front platform of the car within convenient reach 30 of the motorman. The lower end of the lever a projects downwardly a suitable distance beneath the bottom of the car and is provided with a slot a⁶ at its lower end. Loosely pivoted in this slot is a bar a', which is preferably divided and screw-threaded at its adjacent ends and connected by an ordinary turn-buckle a², whereby proper adjustment of the same can be effected. The inner end of the rod a' is sleeved in the lower extremity of a 35 suitable hanger a³, which is secured to the bottom of the car. The inner end of the rod a' is adapted to support a bell a⁴, which may be of any ordinary or preferred construction.

Fixed to the axle of the car or connected

therewith in any desired manner are two radial arms or rods provided with strikers B at the ends thereof, which may be of any desired shape, and said arms or rods are preferably resilient to facilitate the operation thereof, and said strikers are adapted to come 55 in contact with the bell or gong on the rear end of the rod a' during the revolution of the axle, as hereinafter described.

To the lower part of the foot-lever a is secured one end of a helical spring a⁵, the other 60 end of which is secured in any suitable manner to the forward part of the car.

From the above description it will be seen that by pressing the foot upon the foot-lever a the rod a' will be caused to move backwardly, 65 carrying the bell a⁴ into the path of the revolving striking-lugs B. So long as the bell is held in this rearward position it is obvious that it will continue to sound so long as the car is in motion or until the pressure is removed from the foot-lever a, when the spring a⁵ will restore the bell to its normal or retracted position.

Having fully described my invention, I claim as new and desire to secure by Letters 75 Patent—

1. The combination with a car, of an alarm mechanism, comprising a slot formed in the platform of the car, a lever pivoted therein and projecting downwardly therethrough, a 80 rod pivotally connected with said lever and extending backwardly through a suitable support connected with the bottom of the car and in which said rod is longitudinally movable, a bell or gong connected with the rear 85 end of said rod, and strikers connected with the axle of the car, adjacent to said rear end of said rod and adapted to operate in connection with said bell or gong, said rod being composed of separate adjustable sections, substantially as shown and described.

2. In a mechanism for operating an alarm-bell, the combination with a car, of a foot-lever pivoted in the bottom thereof and provided with a slot in its lower end, a rod engaging the slotted end of said foot-lever, a suitable support for said rod, means for regulating the length of said rod, a bell arranged upon the

inner end of said rod, a retracting-spring connecting the foot-lever with the car, a striking-lug fixed to the axle of the car, the construction and arrangement being such that when 5 the lever is operated the bell is thrown into or out of the path of the striking-lug, substantially as described.

In testimony that I claim the foregoing as

my invention I have signed my name, in presence of the subscribing witnesses, this 4th day 10 of April, 1898.

GEORGE KLEIN, JR.
